UNITED STATES PATENT OFFICE

NICHOLAS L. ETTEM, OF WATERLOO, IOWA, ASSIGNOR, BY MESNE ASSIGNMENTS, TO
CHAMBERLAIN MACHINE WORKS, A CORPORATION

IRONING MACHINE

Application filed May 20, 1929. Serial No. 364,504.

My invention relates to that class of ironing machines in which the ironing process is effected by pressing the garment to be ironed between a head and the buck, the heat for ironing purposes being applied to one of these members.

In machines of this kind it is essential that a relatively great amount of pressure be applied to the garment during the ironing process.

Heretofore ironing machines of this character have been equipped with electric motors or the like of considerable power and weight for the purpose of providing the necessary amount of pressure.

The object of my invention is to provide an ironing machine of the presser type of simple, durable and inexpensive construction, and in which an ample amount of power for pressing purposes may be obtained by the use of a relatively small light-electric motor, which is applied directly to the buck member of the ironing machine, and moves it upwardly only a slight distance to effect the pressing operation, thus providing an ironing machine of very light weight and inexpensive construction.

Another object of my invention is to provide an ironing machine of this character without safety guards and so arranged that it is practically impossible for an operator to get his fingers caught between the presser head and buck during the time that pressure is being applied.

My invention consists in the construction, arrangement and combination of the various parts of the device, whereby the objects contemplated are attained, as hereinafter more fully set forth, pointed out in my claims, and illustrated in the accompanying drawings, in which:

Figure 1 shows an end elevation partly in section illustrating my improved ironing machine.

Figure 2 shows an enlarged detail view in

vertical transverse section illustrating the upper portion of the machine frame and the buck and head members therein.

Figure 3 shows a longitudinal sectional view through the upper portion of the machine.

Figure 4 shows an enlarged detail view in vertical section illustrating the cam shaft and mechanism for actuating it.

Figure 5 shows an enlarged detail view illustrating the motor shaft and the cam shaft and the mechanism for driving the cam shaft at times from the motor.

Figure 6 shows an enlarged detail view illustrating one of the latch devices for securing the frame of the head member to the frame of the buck member. The dotted lines show the latch in open position.

Figure 7 shows a detail sectional view of the hinge member connecting the frame of the head to the frame of the buck member. The dotted lines show a portion of the head member in open position.

Figure 8 shows an enlarged detail view of the cam shaft and one of the cams, and a portion of the means for elevating the buck member by the cam.

Figure 9 shows an enlarged detail sectional view of the latch device for throwing the cam shaft driving pawl out of operative position; and

Figure 10 shows a similar view with the pin withdrawn to permit the latch device to remain in an operative position.

Referring to the accompanying drawings, I have used the reference numeral 10 to indicate the machine frame. Mounted within the lower portion of the machine frame is an electric motor 11 of comparatively light weight and small size. This motor has its shaft 12 projected upwardly and provided on its upper end with a worm gear 13. This worm gear 13 is in mesh with a larger worm gear 14 rotatively mounted on a horizontal cam shaft 15, and means are provided to be

hereinafter described for at times clutching this worm gear 14 to the shaft 15.

Mounted upon each end of the cam shaft 15 is a cam 16 designed to engage a sliding block 17 mounted for movement in a tubular frame 18, fixed to the frame. Received in the upper end of the tubular member 18 is a tubular guide member 19 fixed to the buck member, and between the buck member and the block 17 is a compression spring 20.

By this arrangement it will be seen that when the cam shaft 15 is rotated a half revolution, and the buck member is at its lower position of movement, then the buck member will be raised thereby to its upward limit of movement, and after the head member is fixed in position, then it will limit the upward movement of the buck member and the springs 20 will be compressed to an extent depending upon the thickness of the material inserted between the two pressing members. Then when the cam shaft 15 is rotated again through a half revolution, the buck member will be thereby moved to its lower limit of movement.

In this connection it should be explained that one of the reasons why I am enabled to obtain an adequate pressure for ironing purposes by the use of a very small motor and light and inexpensive frame, is that the entire buck member moves only from one limit to the other about one-fourth inch, and hence the entire power of the motor through many revolutions is reduced by the worm gear mechanism and the cams to such extent as to impart to the buck member only the slight upward movement before mentioned.

For the purpose of causing the cam shaft to be moved through a half revolution, and then stopped, I have provided the following mechanism:

I have provided a casing member 21 for the worm gear 14. Within this casing member there is fixed to the shaft 15 a ratchet member 22, and carried by the worm gear 14 is a pawl member 23 having its end 24 designed to engage and coat with the ratchet member 22, and also having at its opposite end a projecting shoulder 25 for purposes hereinafter made clear. This pawl, is yieldingly held by a spring 26 in position to operatively engage with the ratchet member 22.

Mounted in the casing member 21 is a stationary pin 27, and this pin engages the shoulder 25 of the pawl 23 when it is at its lower limit of movement to thereby overcome the pressure of the spring 26, and hold the pawl 23 out of engagement with the ratchet member 22.

Mounted upon the casing member 21, near its top, is a latch member 28 pivoted at one end at 29, and having an opening 30 in its other end, and also having an arm 31 at the end opposite from the pivot 29. A spring 32

is provided for normally holding this latch member to its upward limit of movement out of the path of travel of the pawl 23, but when said latch member is at its lower limit of movement, its arm 31 will engage the shoulder 25 of the pawl 23 and force the pawl against its spring pressure to position for disengaging the ratchet member 22.

For the purpose of at times holding the latch member 28 at its downward limit, I have provided a sliding pin 33 mounted in the casing 21, and yieldingly held inwardly by a spring 34, and obviously when the pin is at its inward limit of movement, where it is normally held by the spring 34, it will hold the latch 28 in position to engage the ratchet member 23, but when said pin is removed or drawn outwardly, then the spring 32 holds the latch member upward out of the path of travel of the pawl 23. The inner end of the pin 33 is slightly rounded, as shown in Figure 9, so it will readily enter the opening in the latch member 28.

By this arrangement it will be seen that when the pin 33 is at its outer limit of movement, as shown in Figure 10, the latch 28 is held by its spring at its upper limit of movement, as shown in Figure 10, where it will not be engaged by the pawl 23, and this will permit the spring of the pawl 23 to hold the pawl in position so it will engage the nearest shoulder on the ratchet 22, and hence the ratchet will be carried around by the pawl, and the cams on the shaft 15 will be turned and the buck moved. Then when the gear wheel 14 has moved through a half revolution, the pawl 23 will strike the stationary pin 27 and throw the pawl 23 out of engagement with the ratchet 22, thereby stopping the movement of the shaft 15, after it has made a half revolution.

As soon as the operator observes that the buck has commenced to move, then he releases the pin 33, and this pin is then forced by its spring 34 into the opening in the latch 28. The rounded lower edge of the pin 33, as shown in Figure 10, causes this movement of the pin to swing the free end of the latch downwardly until the pin enters the opening in the latch and holds it at its downward movement, as shown in Figure 9. Thereupon, and during each revolution of the gear 14, the pawl 28 will be tipped away from the ratchet 22 when the pawl is in its upper limit by engagement with the latch. Then when the pawl is in its downward limit by engagement with the pin 27, as shown in Figure 5, this operation will continue indefinitely without further movement of the buck.

When it is desired to move the buck in the opposite direction, the pin 33 is again pulled outwardly by the operator until the buck starts to move, and is then released and the operation continues as before with the buck

moved to its opposite limit of movement and there stopped.

By this arrangement the cams 16 will be rotated through a half revolution. When 5 they are in position for holding the buck member at its upper limit of movement, they will be held stationary in this position during any number of revolutions to the worm gear 14, and until the pin 33 is again withdrawn 10 to release the latch member 28, so it will engage the latch 22, whereupon the cams 16 are again turned a half revolution and are caused to move the buck member from its upper limit of movement to its lower limit, 15 and the pawl 23 is again thrown into an inoperative position by the engagement of its shoulder 25 with the pin 27.

The buck member is indicated generally by the reference numeral 35 and is preferably 20 provided with the customary pad 36 at its top.

Fixed to the frame member and extended transversely across the top thereof are the frame members 37, both ends of which are 25 extended upwardly at 38.

The head member is indicated generally by the reference numeral 39, and in its closed position it stands spaced apart above the buck member approximately one-fourth inch 30 when the buck member is at its lower limit of movement.

I preferably project the side edges of the head member slightly over and beyond the top of the buck member to form a safety seal 35 device, as hereinafter more fully explained.

This head member is supported by two transverse frame members 40 to which it is firmly fixed. These frame members have both ends extended downwardly at 41. At 40 the rear of the machine these downwardly extended ends are hingedly connected to the upwardly extending ends 38 of the frame members 37, and at the front there is carried by each of these downwardly extended end 45 members 41 a latch member 42, normally held in closed position by a spring 43, and designed to coact with a pin 44 carried by the adjacent frame member 38. These latch members are provided with forwardly extending ends 45, which are connected by a handle 46.

I preferably provide in the head member 39 an electric heating element of ordinary construction not shown.

55 Springs 47 are provided for normally holding the head supporting frame members 40 in an open upright position at the back of the buck member.

In practical operation, and assuming that 60 the head member is in its open upright position wholly at the rear of the buck member, then the operator may readily and easily place the garments to be ironed upon the buck member. Then the operator grasps the 65 handle 46 and moves the head member to

its locked position slightly above the adjacent surface of the buck member.

In this connection let it be assumed that an operator through carelessness has placed his fingers between the head and buck member, then due to the projecting edges of the buck member and the fact that the space between the head and buck members, when they are latched together, is only about one-fourth inch, it is obvious that the operator cannot 70 lower the head member far enough to latch it, and all of the pressure that could be applied with the operator's hand upon the head member to move it to closed position would not injuriously affect the operator's fingers that 75 might happen to be placed between the head and buck members. Hence, the only time that the head member can be moved to its latched or locked position is when there is no obstruction between the head and buck members, such for instance as an operator's fingers.

When the head member is in its locked position, then the operator pulls the pin 33 outwardly, and assuming that the motor is 80 running, then the pawl 23 carried by the worm gear 14 moves the shaft 15 very slowly through a half revolution, and during this movement, the buck member is moved upwardly under great pressure against the 85 firmly positioned head member, and the buck member is then retained in this elevated, tightly compressed position for as long a time as in the opinion of the operator it is necessary to apply heat and pressure for 90 ironing purposes. Then the operator again releases the pin 33 and the buck member is removed to its lowered position, and then the operator manipulates the handle 46 to release the latches 42 and permits the springs to 95 elevate the head member to its original position.

It is obvious that by means of my improvement, and due to the fact that the movement of the buck member is very limited, I am enabled to employ a relatively small electric motor for applying a relatively heavy pressure to the buck member against the locked head member, and due to the fact that the head member is firmly held upon the supporting frame members 37 and 40 at both 100 sides, it is obvious that these frame members will withstand all the pressure which is applied by the buck member against the head member, and yet due to their construction, these frame members may be made of relatively light and inexpensive material, and since practically all of the strains and pressures upon the entire apparatus are carried by these two frame members 37 and 40, the 105 rest of the mechanism may be relatively light and inexpensive.

I claim as my invention:

1. In an ironing machine of the class described, the combination of a frame, two 110 transversely arranged frame members near

the top of the frame having their ends extended upwardly, a buck member carried by the frame, two transverse head member carriers pivoted at one end of the upper ends of said 5 upwardly extending frame member on one side of the buck member, a head member fixed to said carriers, the opposite end of said carriers being extended downwardly at the side opposite from the pivot, spring operated 10 latch members carried by said carriers, a handle connecting them, and coacting latch members carried by the upwardly extended portions of said frame members on the outside of the buck member, said parts being so 15 arranged and constructed that pressure by the buck member upwardly against the head member will be resisted by said frame member and carriers.

2. In an ironing machine, the combination 20 of a buck, means for bodily raising and lowering it, a head mounted to be moved toward and from the buck, a latch device for the head designed to lock the head only in a predetermined working position which is spaced 25 above the lowered position of the buck, and whereby when the buck is in an elevated position or there is an obstruction between the buck and head, the head cannot be latched against upward movement.

3. In an ironing machine the combination 30 of a buck capable of being moved bodily from a predetermined upward limit of movement to a downward limit of movement, manually controlled power operated means for moving 35 said buck, a head mounted to be moved toward and from the buck, a latch device for the head designed to lock the head only in a predetermined working position which is spaced above the lowered position of the buck, 40 and whereby when the buck is in an elevated position or there is an obstruction between the buck and head, the head cannot be latched against upward movement.

NICHOLAS L. ETSEN.
